UNITED STATES PATENT OFFICE.

GEORGE F. TAYLOR, OF WASHINGTON, DISTRICT OF COLUMBIA, DEDICATED, BY MESNE ASSIGNMENTS, TO THE CITIZENS OF THE UNITED STATES OF AMERICA.

RESISTANCE THERMOMETER.

Application filed December 13, 1923. Serial No. 680,472.

(FILED UNDER THE ACT OF MARCH 3, 1883, 22 STAT. L., 625.)

To all whom it may concern:

Be it known that I, GEORGE F. TAYLOR, a citizen of the United States of America, and an employee of the United States Department of Agriculture, residing in the city of Washington, District of Columbia (whose post-office address is Department of Agriculture, Washington, D. C.), have invented a certain new and useful Resistance Thermometer.

This application is made under the act of March 3, 1883, chapter 143 (22 Stat. 625) and the invention herein described and claimed may be used by the Government of the United States or any of its officers or employees in the prosecution of work for the Government, or by any citizen of the United States without payment to me of any royalty thereon.

The object of my invention is to provide a resistance thermometer which is small, of low heat capacity, and short lag, and thoroughly protected from moisture and corrosive gases without the use of a desiccating agent, or chemicals inside the bulb.

The invention will be fully described in connection with the accompanying drawing in which Fig. 1 represents a vertical sectional view of the entire thermometer; Fig. 2 is a top plan view thereof; Fig. 3 is a horizontal sectional view taken on line 3—3 of Fig. 1; Fig. 4 is a horizontal sectional view taken on line 4—4 of Fig. 1, and Fig. 5 is an elevation view of my improved thermometer, actual size.

H is a hard rubber or bakelite head. The upper end of the head is hollowed out, with only a thin flange P left around the edge. This depression, as well as the entire tube A is filled with a wax, which serves to stiffen the tube A, holds the lead wires B and C rigidly in place, and prevents electrical leakage between the studs S due to the formation of moisture films which would form on hard rubber or bakelite. Into the head H fits a glass or metal tube A containing and protecting all the working parts. The metal studs S fit into the upper end of the head H, and to them the lead wires (not shown) from a Wheatstone bridge (not shown) are attached to the upper end of the studs, S, and the leads from the measuring

element are soldered to the lower end of the studs S.

A represents the walls of the protecting tube. I is a mass of metal into which the resistance element K and the ends of the lead wires B and C are embedded. K is the resistance element, which consists of a fine thread of metal drawn in glass. This thread K at its lower end makes electrical contact with the metal in which it is embedded. The filament K at its upper end expands into a slightly larger portion N, at which point it is soldered to the enlarged end of the lead B. Thus the circuit is completed from the lead C through the mass of metal I, through the filament K, to the second lead B. This lead B is enclosed in a small, thick-walled glass tube O with a slight flare at its lower end to hold it firmly in the embedding metal. The lead B has a spherical enlargement just below the end of the tube O. The junction of the lead and filament is covered with a coating of porcelain cement J, which extends some distance into the tube O. The purpose of this arrangement is to insulate these parts from the surrounding metal, hold them firmly in place, and prevent any metal from flowing into the tube O in the process of molding.

I claim:

1. A resistance thermometer, comprising a casing, a head affixed to one end of said casing, a metal body in said casing, a resistance element embedded in said metal body, two lead wires one of which is secured to said resistance element and the other embedded in said metal body, means for preventing contact between the resistance element, its lead wires and said metal body except at the end of the resistance element farthest from the lead wire to which it is secured.

2. A resistance thermometer, comprising a casing, a head, a metal body in said casing, a resistance element embedded in said metal body, two lead wires one of which is secured to said resistance element and the other embedded in said metal body, said head consisting of a cylindrical mass of hard rubber having a hole through its axis adapted to receive and support said casing and said lead wires, the upper end of said

head having affixed thereto two posts and being provided with a flange around the circumference thereof to permit of the reception of a wax filler adapted to insulate 5 said lead wires and said posts.

3. A resistance thermometer, comprising 10 a casing, a head affixed to one end of said casing, a metal body in said casing, a resistance element embedded in said metal body, a glass covering for said resistance element provided with an opening at its upper end to permit the resistance element to be affixed to its lead wire and an opening at its lower 15 end to permit the resistance element to form contact with the metal body, two lead wires

one of which is embedded in said metal body and the other of which has an enlargement at its lower end and at which lower end is affixed the said resistance element, a glass tube surrounding said lead wire having an 20 enlargement, extending from the enlargement to the end of the casing inside the said head, said enlargement on the aforesaid lead wire being provided with a coating of porcelain cement extending from the 25 lower end of said glass tube surrounding the lead wire to the upper end of the glass covering of the resistance element.

GEORGE F. TAYLOR.
